UNITED STATES PATENT OFFICE.

WILLIAM MENDENHALL, OF CINCINNATI, OHIO, ASSIGNOR TO THE MENDENHALL STORE SERVICE COMPANY, OF SAME PLACE.

STORE-SERVICE APPARATUS.

SPECIFICATION forming part of Letters Patent No. 424,327, dated March 25, 1890.

Application filed November 30, 1888. Serial No. 292,204. (No model.)

To all whom it may concern:

Be it known that I, WILLIAM MENDENHALL, a citizen of the United States, residing at Cincinnati, in the county of Hamilton and State of Ohio, have invented certain new and useful Improvements in Store-Service Apparatus, of which the following is a full, clear, and exact description, reference being had to the accompanying drawings, forming part of this specification.

My invention relates to that class of store-service apparatus in which a carrier is propelled upon a way or wire and carries beneath it a detachable receptacle for the articles to be transported; and it has for its object the improvement in the construction and mode of operation of the apparatus.

The novelty of my invention will be here-with set forth, and specifically pointed out in the claims.

In the accompanying drawings, Figure 1 is a side elevation of a store-service apparatus embodying my invention. Fig. 2 is an enlarged side elevation of the carrier and receptacle under one form of construction. Fig. 3 is a corresponding view to Fig. 2 under another form of construction. Fig. 4 is a corresponding view to Fig. 1 with a modification in the construction. Fig. 5 is an enlarged plan view through the dotted line xx of Fig. 4. Fig. 6 is an enlarged detail plan through the dotted line yy of Fig. 4. Fig. 7 is a corresponding view of Fig. 1 with another modification in the construction. Fig. 8 represents a side elevation of a modified form of spring for resetting the propelling-cord. Fig. 9 is a central vertical section of the lower portion of the pendent support for the propelling devices. Fig. 10 is a central vertical section of a portion of said support, showing the employment of a weight instead of a spring for resetting the propelling-cord.

The same letters of reference are used to indicate identical parts in all the figures.

A is the usual vertical tubular post, secured at its upper end to the ceiling or other support and having passed through its lower end and secured to some suitable fixed point one end of the horizontal wire or way B, upon which the carrier and receptacle are pro-

pelled. Secured to and extending from the post A horizontally over the wire B is an arm C, having a bearing a at its extremity, in which is journaled a vertical grooved pulley b . In a bearing c , clamped or secured to the post A, are journaled two grooved pulleys d e , the former horizontal and the latter vertical, (see Fig. 6,) to serve as guides for the operating cord or rope D, which is passed up over the pulleys d e and thence forward over the pulley b , and has its forward end (see Fig. 1) provided with a button-disk or other suitable projection f , which, with the forward end of the cord D, hangs down just over the wire B, as seen by the solid lines.

The carrier is composed of the usual or any suitable bar g , from which extend up the ears h , in which the grooved rollers i are journaled, and by which latter the carrier is supported on the wire B, the pendent arms or hangers j , which carry the cup or receptacle E, in a manner to be presently explained, the upturned forks l near each end of the bar g , and spring-jaws m at each end of the bar g .

When the carrier and its receptacle are propelled across the wire and come in toward the apparatus just described, the button j is caught between the adjacent forks l , and with the cord D is carried back to the position indicated by the dotted lines, and the spring-jaws m slip over a head or enlargement n upon the end of the piston-rod F of the air-cushioning device G. This air-cushion serves to arrest the carrier without shock or jar, and the spring-arms m by their frictional contact with the enlargement n hold the carrier to the rod F.

Upon giving the handle q a quick pull downward the button f is suddenly drawn forward against the forks l of the carrier, and the latter is thereby released from the rod F and propelled across the way to a similar or other suitable receiving and returning apparatus. It is desirable to have a stop for limiting the stroke of the cord D and button f , and to that end I place a button or knot r upon the cord, which is arrested by a slotted or perforated stop-piece s , preferably adjustable upon the rod C, and through which the cord D is strung.

It is of course evident that the spring-jaws

- m* may be upon the end of the rod *F*, in which event the ends of the carrier would have the enlargement to be caught and engaged by said jaws; or, again, the air-cushion might be applied to the carrier, as will be readily understood, in which event the spring-jaws might be upon the post, or, if upon the piston-rod, the post itself might be engaged or be provided with an engaging projection.
- 10 The modifications represented in Figs. 4, 7, and 10 consist in the application of resetting mechanism to return the button *f* back to the post after the carrier has been propelled and as soon as the cord is released. In Fig. 4 the 15 cord is extended back from the button around a guide-pulley *t* and up to a spring *u*, whose upper end is secured, as at *v*. In propelling the carrier the spring *u* is put under tension, so that as soon as the carrier has been propelled by the quick downpull of the cord *D* and the latter is released the button is at once 20 reset or drawn back in readiness to propel the carrier again upon its return, as will be readily understood.
- 25 In Figs. 7 and 8 the same result is accomplished by the substitution of a different form of spring. Here, instead of the rubber or coiled spring of Fig. 4, I employ a spring-drum *J*, attached to the post *A*, and around which 30 a sufficient amount of the rear end of the cord *D* is wound and made fast. The interior of the drum is hollowed out and contains a convolute spring *w*, one end of which is made fast to the drum and the other to its stationary 35 spindle. The turning of the drum as the button goes forward to propel the carrier puts the spring under tension, and upon the release of the cord it resets the parts, as will be readily understood.
- 40 In Fig. 10 I have shown how a weight may be substituted for the spring to reset the button. Here the cord passes back from the button through a perforation in the post and around the pulley *t*, located in the post, thence 45 up over a pulley *a'* in the upper part of the post, and thence downward, and has a weight *b'* secured to its lower end within the post. Slots *p* are cut in the bottom of the post through the apertures *o*, to permit the ready 50 insertion of the wire *B* without the necessity of threading the same, after which the air-cushioning devices and the ornamental plug *I* are applied. The ends of the wire extend back and up and are properly secured, after 55 which and its insertion in the slots *p* the wire is made taut by turn-buckles in the usual manner.
- The remaining features of my invention are illustrated in Figs. 2, 3, and 5.
- 60 In Fig. 3 the supporting-ring *k* for the cup *E* is integral with or secured to the lower ends of the hangers *j*. The cup *E* has upon its side two diametrically-set lugs *c'*, which, when the cup is lifted and inserted through the 65 ring, pass through slots or recesses *d'* upon the inner edge of the ring, so that when the

cup is turned these lugs travel and rest upon the ring, and so support the cup. To prevent the cup from turning while on its way across the wire, that part of the ring at the slots *d'* is 70 made higher than the rest, from which points it slants downward to the hangers, so that when the cup is inserted and turned, as seen in Fig. 3, its gravity would prevent its accidental returning.

75 In Fig. 2 the ring is made fast to or part of the cup and the lower ends of the hangers *j* have inwardly-extending shoulders to fit under and hold up the ring and cup. Here the under side of the ring at its highest points 80 is recessed, as at *e'*, so that when the cup is turned these recesses are caught and fit over the shoulders of the hangers.

85 In Fig. 2 the cup is shown just as it is inserted and before it is turned. Where the ring is upon the hangers, it is of course evident that but one slot *d'* may be employed, in which event the cup would have but one lug.

I do not claim herein specifically the construction shown in Figs. 1 and 5, as the same 90 are embodied and specifically claimed in an application filed by me on the 14th day of October 1889, Serial No. 327,013.

Having thus fully described my invention, I claim—

95 1. In a store-service apparatus, the combination, with a way and a carrier supported thereon, of an arm extending outwardly over said way and provided at its outer end with a guide-pulley over the way, a single propelling-cord passed over said guide-pulley and having a pendent free end adapted to be grasped by the operator, and a button secured upon and supported by said propelling-cord above the way and arranged to engage the carrier to give the latter a sudden 100 impetus to propel it along the way when said cord is operated, substantially as and for the purpose described.

105 2. In a store-service apparatus, the combination, with a way and a carrier supported thereon, of an arm extending outwardly over said way and provided at its outer end with a guide-pulley, a propelling-cord passed over said guide-pulley, a button secured upon and supported by said propelling-cord above said way and arranged to engage the carrier to propel the same along the way, and a spring or weight for resetting said cord after the carrier has been propelled, substantially as and for the purpose described.

110 3. In a store-service apparatus, the combination, with a way and a carrier supported thereon, of an arm extending outwardly over and lengthwise of said way and provided at 115 its outer end with a guide-pulley, a second guide-pulley supported at the inner end of said arm, a propelling-cord passed over said pulleys, a button secured upon and supported by said propelling-cord above said way and arranged to engage the carrier to propel the same along the way, and a spring or weight for resetting

said cord after the carrier has been propelled, substantially as and for the purpose described.

4. In a store-service apparatus, the combination, with a way and a carrier supported thereon, of an arm extending outwardly over and lengthwise of said way and provided at its outer end with a guide-pulley, two guide-pulleys supported at the inner end of said arm, a propelling-cord passed around said outer pulley and having its opposite inner ends passed one over each of said inner pulleys, a resetting spring or weight connected to one of the ends of said cord, and a propelling-button secured upon and supported by said cord and normally held suspended over the way, substantially as and for the purpose described.

5. In a store-service apparatus, the combination, with the way B and the carrier supported thereon and provided with the upwardly-extending forks l, of the support A, arm C, extending outwardly over the way B and provided at its outer end with the guide-pulley b over the way, the single propelling-cord D, passed over said pulley and over a second pulley at the inner end of the arm C and having a pendent free end adapted to be grasped by the operator; and a button f, secured upon and supported by the propelling-cord D above the way B and arranged to engage the upwardly-extending forks l of the carrier to give the latter a sudden impetus to propel it forward along the way when said cord is operated, substantially as and for the purpose described.

6. In a store-service apparatus, the combination of the support A, the outwardly-extending arm C, provided at its outer end with

the pulley b, the pulleys supported at the inner end of the arm C, the propelling-cord D, passed around the pulley b and over the pulleys at the inner end of the arm C and provided with the button f, secured upon and supported by said cord above the way B, the resetting-spring connected to one end of said cord, the way B, and the carrier supported on said way and arranged to be engaged by the button f on the propelling-cord, substantially as and for the purpose described.

7. In a store-service apparatus, the combination of the support A, the laterally-extending arm C, provided at its outer end with the guide-pulley b, the pulleys d, e, and t, carried in bearings secured to the support A, the propelling-cord D, passed around the pulley b and having one of its inner ends passed over the pulleys d e and downward and the other over the pulley t and upward, the resetting-spring u, secured to the upward-extending end of the cord D, the button f, secured to said cord, the way B, and the carrier supported thereon and arranged to be engaged by the button f on the propelling-cord, substantially as and for the purpose described.

8. In a store-service apparatus, the combination of the carrier having the downwardly-extending hangers j, provided with the ring k, slotted at d' and slanting downward from said point, and the receptacle E, fitting in said ring and having secured to it the lugs e', arranged to engage the ring, substantially as and for the purpose described.
